(57) CLAIM

The ornamental design for a automatic switching device, as shown and described.

DESCRIPTION

There is provided an automatic switching device mainly for automatically switching between two or more sets of computer equipment.

FIG. 1 is a perspective view of an automatic switching device showing my design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof; and,

FIG. 9 is a further perspective view of the automatic switching device of my design in an upright position for use.
